UNITED STATES PATENT OFFICE.

ADOLF HIRSCH, OF NEW YORK, N. Y.

DESIGN FOR A FLAG.

51,342.

Specification for Design.

Patented Oct. 9, 1917.

Application filed August 10, 1917. Serial No. 185,614. Term of patent 3½ years.

To all whom it may concern:

Be it known that I, ADOLF HIRSCH, a citizen of the United States, and a resident of the city of New York, borough of Manhattan, in the county and State of New York, have invented a new, original, and ornamental Design for a Flag, of which the following is a specification, reference being had to the accompanying drawing, forming part thereof.

The figure is a face view of a flag embodying my new design.

I claim:

The ornamental design for a flag, as shown.

ADOLF HIRSCH.
